AIR CONDITIONING APPARATUS

Lester S. Keilholtz and Le Roy A. Volberding,
Detroit, Mich., assignors, by mesne assign-
ments, to Borg-Warner Corporation, a corpo-
ration of Illinois

Application January 19, 1934, Serial No. 707,294

1 Claim. (Cl. 261—115)

This invention relates to air conditioning and particularly to improvements in apparatus of a semi-portable type for humidifying, circulating and purifying the air of enclosed spaces such as 5 rooms, homes and offices.

This invention has particular reference to relatively small units adaptable for use in homes and offices and the parts of which are compactly arranged so that the unit occupies a very 10 small amount of space and so that the unit can be placed into use with very little installation expense and which does not require any alterations or modifications of the room in which such a device might be installed.

15 This invention has as a principal object thereof the provision of an air conditioning unit provided with a spray nozzle and means serving as a support therefor, said means serving also as a means for disposing of the nozzle drippings 20 toward the casing walls, and adapted to be used in conjunction with the means now normally provided in homes and offices for heating and ventilating.

25 This invention contemplates the provision of a unitary structure comprising a casing providing a spray chamber, means for supplying water to the spray chamber wherein the water is atomized, means for supporting an ordinary spray nozzle which is used in an air conditioning unit, 30 said means also serving as a disposing means for unatomized water which has collected upon the spray nozzle, and any other apparatus which is ordinarily used in an air conditioning unit.

35 An object of this invention, therefore, is the provision of a semi-portable unit air conditioning apparatus which is practically adaptable for universal installation, and which is provided with means for preventing unatomized water from being discharged into the area being conditioned.

40 Another object of the invention is the provision of an air conditioning unit in which the parts thereof are compactly and conveniently arranged for assembling in manufacture and dis- assembling for periodic cleaning purposes.

45 Other objects and advantages will be apparent from the following specification taken in connection with the drawings, of which there are two sheets and in which:

Fig. 1 is a more or less diagrammatic view of 50 a typical installation of a device embodying the inventions herein disclosed;

Fig. 2 is a front elevational view, partly bro- ken away, of a device embracing the invention;

Fig. 3 is a side elevational view, partly bro- ken away, of an apparatus embracing the inven-

tion and illustrating certain particulars there- of in detail;

Fig. 4 is a more or less diagrammatic view of the blower motor speed control means and the wiring connection for the unit;

Fig. 5 is a horizontal partial sectional view of the air inlet filter taken generally on the line 5—5 of Fig. 3, looking in the direction of the arrows;

Fig. 6 is an elevational view of the air inlet 10 filter and taken in a plane on the line 6—6 of Fig. 3; and

Fig. 7 is a top plan view of the air inlet filter, taken on the line 7—7 of Fig. 3.

Referring now particularly to Fig. 1 of the 15 drawings, there is shown, for the purposes of illustration, a diagrammatic view of a type of installation of an air conditioning unit embracing the inventions herein disclosed and in which a unit 12 is shown mounted upon the floor of a 20 room and having an electrical conduit 14 connected to any suitable source of electrical energy such as an electric outlet 16, a control knob 18 for regulating the speed of the blower motor, a water feed pipe 20 connected to a source of cold 25 water 22 and a source of hot water 24, and a waste water pipe 26 for carrying excess water to any suitable drain. The hot water may be supplied by any suitable means such as an indirect heater 28 of any well known construction 30 and which is shown as associated with a steam plant 30 below the water line thereof. The temperature of the feed water passing through pipe 20 may be determined by a thermometer 32 disposed in a well 33 and may be varied by adjust- 35 ment of valves 34 disposed in the hot and cold water supply lines. The waste water pipe 26 may be provided with an overflow T 36 to permit the escape of water from the unit in the event the waste water pipe 26 becomes clogged 40 below the level of the T 36.

The unit 12 in general comprises an inner casing 38 affording a spray chamber, and to the lower end of which leg brackets 40 may suitably be secured for supporting the same upon a floor surface, a blower assembly 42 disposed in an upper forward portion of the inner casing 38 and for creating a circulation of air therethrough, and sound-absorbing filter boxes 44 disposed one on each side of the inner casing 38 and providing 50 air inlet passageways to the blower assembly 42, an outlet hood 46 of sound-absorbing material disposed above the inner casing 38 and providing a series of passageways between the discharge outlet of the casing 38 and a grilled opening af- 55

fored in the upper portion of an outer casing 48 which is adapted to envelop the inner casing and the controls therefor, and a rheostat 50 connected in series with the blower motor for controlling the speed thereof.

5 The feed water pipe 20 is connected to a water strainer 54 disposed beneath the casing 38 and between the leg brackets 40 from whence the water is conducted to a pressure regulating valve 10 56 and then to a standpipe 58 disposed within the casing 38 extending upwardly and rearwardly from a central forward portion of the bottom of the casing 38 to a point approximately midway of the walls of the casing 38 where it is provided with a spray nozzle 60 which is adapted to create a conical-shaped spray about the standpipe 58 as an axis and within the bottom portion 15 of the casing 38.

Water is supplied to the spray nozzle 60 under 20 pressure, which may be varied, where a stream of water is directed against a target 62 having a concave end surface which is adapted to reverse the direction of flow of the water and create a conical-shaped film which at its outer edges 25 bursts into a fine spray of liquid particles within the bottom of the casing 38. The target 62 on the spray nozzle, which is the center of the region of formation of the spray is spaced from the walls of the casing 38 so that the spray strikes 30 the same at least a certain minimum distance from the region of formation whereby the pressure of the feed water is considerably spent before it contacts the walls of the inner casing 38, as a result of which a minimum of noise is 35 created.

For the purpose of securing the location of the nozzle 60 within the casing 38, a brace 66 secured to the bottom of the casing 38 is connected to a portion of the spray nozzle 60 and also serves 40 as a drip guide therefor to eliminate the dripping of water from the spray nozzle which normally would create considerable objectionable noise as a result of the impingement of drops of water upon the bottom of the metallic casing 38.

45 The blower assembly 42 is disposed within an upper forward portion of the casing 38 and in general comprises laterally spaced blower housings 68 mounted upon a sloping plate 70 which is adapted to rest upon brackets 72 provided by 50 the front and side walls of the casing 38 and by a transverse wall 74 extending from side to side of the casing 38 and disposed to the rear of the median plane thereof. The housings 68 are provided with openings at their lower ends which 55 register with openings provided in plate 70 whereby air is discharged downwardly into the casing 38 along the front wall thereof and forwardly of the spray nozzle 60, where the air enters the region of the conical spray formation, 60 is reversed in its direction of flow by the curved bottom of the casing 38 and flows upwardly along the rear wall of the casing 38 and rearwardly of the spray nozzle 60 where it passes out of the region of the spray and between the rear wall 65 of the casing 38 and transverse wall 74. In passing through the casing 38, the air is passed across the spray as a result of which dirt entrained in the air is precipitated out of the air current and washed with the surplus water into 70 a drain 76 open to the bottom of the casing 38 and connected with the waste pipe 26.

An electric motor 78 having a shaft 80 extending from each end thereof is resiliently mounted in floating rubber bushings 82 carried by flexible 75 supporting arms 84 which are fixedly secured to

the sloping panel 70 and between the blower housing 68. Each end of the motor shaft 80 extends within one of the blower housings 68 and has secured thereto a blower wheel 86 which, upon rotation, are adapted to discharge a blast 5 of air downwardly and out of the blower casing 68 into the region of the inner casing 38 forwardly of the spray nozzle 60 and along the front wall. The blower wheels 86 at their periphery are provided with a plurality of arcuate forwardly extending blades 87 and at the end farthest removed from the motor 78 are open for drawing into the housing 68 a stream of air through an opening 88 therein, which openings coincide with openings 90 provided in the side 10 walls of the inner casing 38 and which lead to the interior of the sound-absorbing air filter boxes 44 which at their opposite ends are in communication with atmosphere adjacent the lower portion of the unit 12. Both sides of the blower 20 housing 68 adjacent the electric motor 78 are closed by disk members 92 through which the motor shaft 80 extends, so that in assembly the blower wheels 86 may be mounted upon the motor shaft 80 and then introduced into the blower 25 housings 68 through the openings which the disk member 92 is adapted to close. The top of the blower housing compartment is provided with a plate 94 which closes that space enclosed between wall 74, the front wall of casing 38, and 30 the side walls thereof.

The sound-absorbing air filter boxes 44 may be constructed of suitable slabs of sound-absorbing soft fibrous material and shaped to form a rectangular box, open at one end. Each of 35 the boxes 44 is provided with circular openings 89 in one wall thereof which are adapted to coincide with openings 90 provided in the inner casing 38 so that air may enter the casing 38 along the path indicated by the arrows in Fig. 40 2 through the open end of the box 44, the opening 90 in the inner casing 38, and the blower housings 68 where the air is discharged downwardly through the openings in the sloping plate 70 into the spray chamber. The sound-absorbing 45 inlet boxes 44 may be secured to the sides of the casing 38 by sheet metal clips 96 which are bolted to the side walls of the casing 38. These clips 96 are so arranged that the boxes 44 may readily be removed from and replaced 50 on the unit for periodic cleaning purposes. The surface of the air passageway provided by the sound-absorbing box 44 preferably is rough, to aid in deadening the noises attending the flow of air as well as to assist in filtering the air by precipitating fine particles of dirt. 55

In each of the sound-absorbing air inlet boxes 44, there is removably disposed a low resistance filter 98 having a relatively large surface area and for removing from the air prior to its entry 60 into the casing 38 the sticky, sooty, dirt commonly entrained in air. The air inlet filters 98 comprise V-shaped frames having spaced-apart channel members 100 and 102 in frictional engagement with the inner side walls of inlet boxes 65 44 and between which frame members a strip of screening material 104 is folded back upon itself along the frame from one end thereof to the other and the folds of which are spaced from each other. The side edges of the screening 70 material 104 lie within the channel portion of the frame members 100 and 102 and in that way the passage of air around the screening material is prevented. The frame of the filter is adapted snugly to fit between the opposite side 75

walls of the air inlet boxes 44 so that no air may pass between the frame and the walls of the air inlet boxes 44. The screening material may be secured to the channel members 100 and 102 as by soldering at every few turns. The spaced-apart ends of the V-frame may be connected by angle iron frame members 106 which are adapted to overlie the edges of the air inlet boxes 44 for the purpose of positioning the filter 10 within the air inlet box. The apex of the filter frame terminates slightly below the circular openings 89 leading to the openings 88 and 90.

In passing through the filter, the air is deflected so as to pass more or less laterally 15 through the filter material at an unobstructed portion thereof, such as the bends on the inside of the filter, while the particles of foreign matter tend to precipitate themselves out of the air stream, as the same is deflected, by collecting 20 upon the outside folds of the filter material which offers a substantially high resistance to the passage of the same therethrough.

The electric motor 78 is connected in series 25 with a rheostat 50 which is fixedly secured to a front wall portion of the inner casing 38 forwardly of the motor 78 and may be provided with a shaft 110 for extending through an aperture in the outer casing 48 and to which the control knob 18 is secured for regulating the speed 30 of the blower motor 78. A change in the speed of the motor 78 will vary the velocity of the air discharged from the blower housings 68, with the result that the volume of air passed through 35 the unit may be increased or decreased by controlling the speed of the motor. Since the unit is adapted for use in a substantially enclosed space, it will be apparent that the relative humidity of the air within the enclosed space can be changed or controlled by regulating the quantity 40 of air which passes through the unit. It, of course, will be understood that the air discharged from the blower housings and passed through the water spray will evaporate a substantial amount 45 of water, depending upon such factors as water temperature, water pressure and the diameter of the spray nozzle water orifice. In the unit disclosed in the drawings, the pressure regulating valve 56 may be adjusted for varying the pressure with which water is delivered to the spray 50 nozzle, as may the temperature of the water be controlled by adjustment of the valves 34.

After the air passes upwardly out of the spray region along the rear wall of the casing 38, it passes rearwardly of transverse wall 74 where a 55 free moisture eliminator and scrubber plate 112 is disposed for removing free moisture and dirt from the air currents by precipitation. It will be observed that the bottom portions of the blower housing compartment and plate 70, as well 60 as the eliminator 112, are sloped toward the walls of the casing 38 so that such water as collects upon such a part will be carried to the walls of the casing instead of dripping as they otherwise would do.

The upper portion of the unit is provided with a sound-absorbing outlet box 46 which comprises a sheet metal housing 114 suitably secured above the casing 38 and enclosing a box constructed of sound-absorbing material which is adapted to provide a plurality of passageways 116 between the discharge outlet of the casing 38 and an opening 118 provided in an upper portion of the outer casing 48. The opening 118 may be provided with a grille 120 secured to the casing 48 by depending flanges 122. The housing 114 is provided with an opening below the grille 120 and which opening may be of reduced cross sectional area for the purpose of increasing the velocity of the air as it is discharged from the unit. 10 15

The passageways 116 are formed between slabs 124 of sound-absorbing material, which are spaced apart at their edges by strips of similar material 126 to form a more or less tortuous passageway or outlet from the inner casing which assists in 20 preventing the transmission of noises resulting from the operation of the unit outside of the same. The slabs 124 of sound-absorbing material, as well as the strips 126, may be secured together in a suitable manner such as by gluing and pinning, 25 so that the housing 114 and the box 46 may be removed as a unit. After the air discharged from the outlet box 46 leaves the opening provided in the hood 114, it passes through the grille, which may be used for the purpose of controlling the 30 direction in which the air is discharged into the enclosed space.

In order to prevent stratification of the enclosed air, it is desirable that the air discharged from the unit be deflected upwardly in such a 35 manner that it effects a gentle circulation of the enclosed air which is further aided by the suction of air in through the opening provided in the inlet boxes 44 adjacent the lower portion of the unit. 40

While several specific embodiments of our invention have been illustrated and described, it must be appreciated that many modifications may be made in the construction thereof without departing from the scope of the invention, and for 45 that reason we do not desire to be limited to any particular form or arrangement except in so far as such limitations are included in the following claim:

We claim:—

In an air conditioning unit, the combination of a casing affording a spray chamber with a spray nozzle disposed within said chamber and adapted to create a spray formation therein, a feed water conduit for supplying water to said spray 55 nozzle, and a brace connected to said casing and to said spray nozzle for securing the nozzle against accidental displacement, said brace affording a means for conveying water collecting upon said spray nozzle to a point adjacent the inner walls 60 of said casing.

LESTER S. KEILHOLTZ.
LE ROY A. VOLBERDING.
